WALLACE E. DAY

BY
Chas. E. Townsend

ATTORNEY

UNITED STATES PATENT OFFICE.

WALLACE E. DAY, OF SAN FRANCISCO, CALIFORNIA, ASSIGNOR TO SPENCER ELEVATOR COMPANY, OF SAN FRANCISCO, CALIFORNIA.

ELEVATOR SAFETY APPLIANCE.

Application filed November 15, 1921. Serial No. 515,371.

To all whom it may concern:

Be it known that I, WALLACE E. DAY, a citizen of the United States, residing at the city and county of San Francisco and State 5 of California, have invented new and useful Improvements in Elevator Safety Appliances, of which the following is a specification.

This invention relates to automatic elevators and particularly pertains to a non-interference control system therefor.

In the operation of most automatic elevators at the present time a prospective passenger presses a floor button which brings 15 the elevator to the respective floor and permits the passenger to pass through the floor door and the elevator car door thus gaining access to the car after which the passenger presses one of the floor buttons within the 20 car thus determining the destination of the elevator. If it so happens that a person at another floor presses the floor button before the occupant of the car has time to press the elevator button the control of the elevator 25 is taken away from the occupant of the car and unless he has the presence of mind to press the emergency button the car will be under the control of a prospective passenger at another floor. It is the principal object of the present invention therefore to provide a system of automatic elevator control whereby the prospective passenger will have complete control of the elevator from the time he enters the elevator 30 car until the time he leaves the elevator car at his destination.

The present invention contemplates the use of the usual floor button circuit for producing initial operation of the car safety 40 circuits for preventing a car from leaving a floor without safety and the floor button circuits controlled from within the car. In addition to these circuits, a non-interference control circuit is provided which automatically operates when the elevator door is 45 opened to render the floor button circuits incomplete until the passenger leaves the car and closes the door.

The invention is illustrated by way of example in the accompanying drawing in

which the figure is a view of the wiring diagram disclosing the present invention and its relation to the automatic elevator control system.

Referring more particularly to the drawing, 10 indicates main feed wire connecting with a contact arm 11 of a main control circuit breaker "A." This feed wire also connects with a wire 12 communicating with the coil of a magnet 13. The circuit through this magnet is completed along a wire 14 through a series of floor door contact switches 15. It is to be understood that these switches are all in series and are disposed one at each floor so that the opening of the door will open the switch and break the circuit through the magnet 13. The circuit is completed along a conductor 16 to the opposite feed wire, here indicated at 17. It will thus be evident that the circuit of the circuit breaker "A" is normally closed and will only be opened when one of the elevator shaft floor doors is opened, the magnet 13 being in a normally closed circuit holds the contact 18 of the arm 11 in engagement and thus establishes a circuit from conductor 10 along wire 19 to wire 20. These wires are electrically connected to the arm 21. The circuit then continues along wire 22 to contacts 23, carried by the arm of the car button circuit breaker "C." The fixed one of these contacts connects with a wire 24 forming a common lead wire to a set of floor switches 25, one of which switches is disposed at every floor. These switches are 45 of course provided with separate lead wires 26 connecting with magnet coils 27 which coils act upon switches 28 to close a circuit through a lead wire 29 in a manner which will be hereinafter described.

The opposite poles of the various magnets 27 are provided with conductors 30 leading to separate brushes 31 of a rotary switch unit 32. This unit, as commonly built, has contact segments 33 and 34 through which circuits may be completed to either a "Down" direction magnet 35 along a conductor 36 or an "Up" direction magnet 37 along a conductor 38. The magnet circuit in either event is completed by a wire 39 50

leading to the normally engaged contacts 40 closed by the control arm 41 of circuit breaker "D," the circuit being completed to the feed wire 17 along a conductor 42.

5 The control system is, of course, fitted with the usual emergency control switch 43 and the car door contact switch 44. The switch 43 may be actuated by a button within the car while the switch 44 is normally closed when the door of the car is closed. These switches are included in the following circuit:

From lead wire 10 along the wire 45 to conductor 46, from thence to the emergency control switch 43 to the car door switch 44, then along conductor 47 to magnet 48 of the switch "D" then returning to the negative lead wire along conductor 42.

15 The motor 48^a is provided with reversing switches generally indicated at "E." These switches are actuated by the reversing magnets 35 and 37 and are included in a circuit from the lead wire 10 to the normally closed contacts 18 of arm 11, from thence to conductor 29 which is the common lead wire to the circuit closing switches actuated by the various magnets 27, the circuit from these magnets being traced through the floor switches.

20 30 The circuit breaker "C" is provided to render the floor buttons inoperative when the floor door has been closed and if the car door is opened. This is included in a circuit from conductor 10 through the normally closed contacts 18 of the control circuit breaker "A", then along conductor 19 to conductor 20. The circuit then continues through the normally opened contacts 49 of arm 41, to conductor 50, the 35 normally open contacts 49 being then closed by the breaking of the circuit through the magnet 48 by the opening of the car door and the operation of the contact switch 44. This wire connects with a wire 51 leading 40 to a magnet 52. The circuit is completed through conductor 42 to the lead wire 17. This action will separate the contacts 23 and will bring contacts 53 into engagement.

45 50 The separation of contacts 23 will break the floor button circuit while the contact of members 53 will permit a new circuit to be later established when the car floor button is pressed. This will take place from wire 10 through contacts 18 to wire 19, 20 through conductor 54 and to coil 62. This 55 establishes and maintains an independent circuit for magnet 52.

55 In operation of the present invention it will be assumed that the car is above the first floor and a passenger is on first floor and wishes to be carried to the fourth floor. In that event the following circuits will be established and broken. It is to be understood that the floor door circuit and the car door circuit are both normally ener-

gized; the first of these circuits may be traced as follows:

The current passes along the lead wire 10 to the wire 12, then through the magnet 13 to energize it and normally close the circuit through contacts 18. The current from the magnet will then pass along wire 14 to the floor door contacts 15. These contact switches are normally closed and are wired in series. The circuit is then completed along wire 16 to the lead wire 17.

70 75 The normally closed car door and emergency switch circuit passes along wire 10, then along wires 45 and 46 to the car emergency switch 43, then through the car door contact switch 44 and along the wire 47, through the magnet 48 to the wire 42 and then to the lead wire 17. This will energize magnet 48 and hold the contacts 40 closed while separating contacts 49.

80 85 The car may then be brought to the floor by pressing the first floor button. This will complete a circuit from the positive lead 10 to contacts 18, thence along wires 19 and 20 to wire 22 which connects with the movable contact member 23. This member is normally in engagement with the fixed contact member 23 through which the circuit passes along wire 24 to the floor button and then along its respective conductor 26 to a control switch 28. From thence along a conductor 30 to its brush 31 making electrical connection with wire 36 through the contact segment 33. The current then passes through the coil 35 of the "Down" direction switch and is completed along the return wire 39 to contacts 40, from thence to conductor 42 and the lead wire 17. The completion of this circuit will energize the proper coil 27 thereafter directly establishing a circuit from the wire 26 to the lead wire 29.

90 95 100 The elevator operating circuit will then be held closed while the elevator moves to the first floor. The floor door is then opened. This will break the floor door circuit, previously described, and will de-energize magnet 13, releasing arm 11 and separating contacts 18. The main elevator control circuit will then be interrupted. 105 The car door is then opened thus de-energizing magnet 48 which will release the arm 41 and separate contacts 40 at the same time bringing contacts 49 into engagement.

110 115 The floor door may then be closed and this will immediately close the floor door switch 15, re-energizing magnet 13 and partially re-establishing the control circuits, at the same time a non-interference circuit will be established as follows:

120 125 From lead wire 10 to contacts 18, thence along wire 19 to conductor 20, then through contacts 49 to the wire 50, from thence through the wire 51 to the magnet 52, thereafter returning to the other lead wire 17.

along wire 42. This will instantly cause the coil 52 to be energized establishing contact between the members 53 and breaking contact between the members 23. The floor button switch circuit will then be broken and it will be impossible for a person at any floor to obtain control of the car. The car door is then closed thus completing the original car door and emergency contact circuit previously described. One of the car buttons may be then pushed to close a circuit and elect the destination of the car as for example when pushing the button for the fourth floor the following circuit will be completed:

From conductor 10 through contact 18, to wires 19, 20 and 54, and through magnet 62 to wire 60 and to the elevator car floor button switch. After passing through the switch which has been closed the circuit is completed through a wire 26 to the proper magnet 27, switch 28, then along wire 30 to its brush 30' and through the floor control switch 32 to the wire 38 and the "Up" control magnet 37 thereafter returning along wire 39 through the contacts 40 and wire 42 to the lead wire 17.

The energization of magnet 62 will bring its contacts into engagement and will establish the circuit through the magnet 52 maintaining the contacts 53 closed and the contacts 23 open, which, as previously explained, break the floor button switch circuit and prevent anyone from obtaining control of the car. It will thus be impossible for control of the elevator to be taken away from the operator even though he should let a passenger out at any floor. In that event it will be understood that it might be possible for the outer elevator door to be closed before the inner. When the passenger reaches the intended floor he will of course close the inner door first and then the outer, this tending to establish the original normal circuits and breaking the non-interference circuits to permit the floor button circuits to be cleared. When the non-interfering circuit is broken the magnets 52 and 62 will be de-energized and the circuits controlled by these magnets will be restored to their normal condition.

It may happen that two passengers are in the elevator and one leaves at a floor while the other remains in the car. In this event the inner elevator car door may possibly be closed before the elevator floor door which would result in re-establishing the control of the car by the floor buttons. These buttons may be instantly rendered inoperative by pressing the button of emergency switch 43 thus placing the car in complete control of the passenger.

It will thus be seen that the apparatus here disclosed will make it possible for a

passenger to have complete control of the movement of a car from the time he opens a floor door to enter until such a time as he shall successively close the car door and the floor door upon leaving.

While I have shown the preferred form of my invention as now known to me it will be understood that various changes might be made in the combination, construction, and arrangement of parts by those skilled in the art without departing from the present invention as claimed.

Having thus described my invention, what I claim and desire to secure by Letters Patent, is:

1. In an automatic control for elevators having a driving motor, a series of floor buttons, and associated electric circuits, by which the elevator can be brought to a desired floor, a series of car buttons and associated circuits by which a passenger within the car may cause the car to travel to the desired floor, a circuit breaker in the said associated circuits of the car buttons, and means including an automatically established non-interference circuit having means for operating the said circuit breaker to open the floor button circuits and render the same inoperative from the time a passenger enters a car until he is leaving the car.

2. An automatic elevator control including the combination with an elevator car adapted to travel along an elevator shaft and to stop at various floors, the elevator car being equipped with a normally closed door and the elevator shaft being provided with normally closed doors at the various floors, means for driving the elevator, a normally closed electric floor door circuit adapted to be broken when a floor door is opened, a normally closed car door circuit adapted to be broken when a car door is opened, normally opened floor door button circuits adapted to be selectively closed at each floor to cause the elevator to travel to the respective floors, a normally opened car button circuit adapted to be closed to cause the car to travel to a selected floor, a circuit breaker in the car button circuit and a non-interference circuit having means for operating the said circuit breaker to open the floor button circuits and render the same inoperative from the time a passenger enters the car until he is leaving the car.

3. An automatic elevator control including the combination with an elevator car adapted to travel along an elevator shaft and to stop at various floors, the elevator car being equipped with a normally closed door and the elevator shaft being provided with normally closed doors at the various floors, of means for driving the elevator, a normally closed electric floor door circuit

- adapted to be broken when a floor door is opened, a normally closed car door circuit adapted to be broken when a car door is opened, normally open floor button circuits
5 adapted to be selectively closed at each floor to cause the elevator to travel to the respective floors, a normally open car button circuit adapted to be closed to cause the car to travel to a selected floor and
10 automatic operating means including a non-interference circuit controlling a switch in the floor buttons circuits for rendering the floor button circuits ineffective, said means being rendered operative by the successive closing of the elevator shaft door 15 and the car door and being rendered inoperative by the successive closing of the elevator car door and the shaft door.

WALLACE E. DAY.
